(No Model.)

J. S. JAMESON.
CLOTHES LINE PROP.

No. 372,915.

Patented Nov. 8, 1887.

UNITED STATES PATENT OFFICE.

JOHN S. JAMESON, OF NEW ALBANY, INDIANA, ASSIGNOR OF ONE-HALF
TO ALEXIS LEMMON, SR., OF SAME PLACE.

CLOTHES-LINE PROP.

SPECIFICATION forming part of Letters Patent No. 372,915, dated November 8, 1887.

Application filed March 19, 1887. Serial No. 231,495. (No model.)

To all whom it may concern:

Be it known that I, JOHN S. JAMESON, a citizen of the United States, and a resident of New Albany, in the county of Floyd and State 5 of Indiana, have invented certain new and useful Improvements in Clothes-Line Props; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved jointed clothes-prop, showing the same adjusted in its operative position. Fig. 2 is an enlarged detail view of the upper end of the prop. Fig. 3 is an enlarged detail view of the jointed ends of the prop. Fig. 4 is a perspective view of the upper section of the prop. Fig. 5 is a similar view of the lower half or section; and Fig. 6 is a horizontal sectional view, taken on the line xx of Fig. 3.

The same letters of reference indicate corresponding parts in all the figures.

My invention consists in an improved sectional or jointed clothes-prop, which will be hereinafter fully described and claimed.

Referring to the several parts by letter, A 30 indicates the lower half or section of my improved clothes-prop, and B indicates the upper half of the same. Each of the said sections is preferably made four feet six inches long. The lower end of the lower half, A, of 35 the prop is sharpened, as shown at a , to adapt the lower end of the prop to be readily inserted into the ground, and the upper end of this half is formed with the longitudinal slot A', about one and one-fourth inch in length, while 40 below this slot is screwed into the prop-section a screw, A², having a wide head standing out from the face of the wood about three-fourths of an inch. The edges of this slot A' on the side of the prop opposite to the screw-head are beveled, as shown. The lower end 45 of the upper half or section, B, is also formed with a longitudinal slot, B', about one and one-fourth inch long, and above this slot is screwed into the wood a screw, B², having a broad head, standing out from the wood about three-fourths of an inch, the edges of this slot on the

side opposite the head of screw B² being beveled, as shown. The upper end of this upper section, B, is formed near one edge with a longitudinal slot, B³, forming a side strip, C', and the broadest part, C, of this slotted end is rounded on its upper inner edge at c , and after coming nearly in contact with the side strip, C', at c' is formed with the recess C², running from its inner edge, as shown. The object of this construction is that when the prop has been jointed together, as hereinafter described, and its lower sharpened end inserted in the ground, the rope or clothes-line D is slid into the slotted upper end of the upper section, the side strip, C', 55 which is only one-fifth the width of the prop, will bend outward or "give" sufficiently to permit the rope to move past the point c' to enter the notch or recess C², the strip springing back as soon as the rope passes the point 60 c' , and the prop is thus locked to the rope and prevented from being blown down by the wind or by an accidental push against it. The joints or halves A B of the prop are jointed together by slipping the slotted upper end of the lower 65 half under the screw B² of the upper section and the slotted lower end of the upper section under the screw A² of the lower section, both by the same movement, the beveled edges of the said slots pushing under the broad heads 70 of the said screws, so that the said ends of the sections are thus bound or secured firmly together in a moment. The screws can of course be screwed in to take up wear at any time, so as to always keep the joint perfectly tight and 75 firm. The ends of the sections thus overlapping each other, and having their slotted beveled ends firmly pushed under the broad heads of their screws, it will be seen that they 80 form a firm strong joint, rendering the prop 85 practically one piece in operation.

From the foregoing description, taken in connection with the accompanying drawings, the construction and advantages of my improved jointed clothes-prop will be readily 90 understood. It will be seen that it can be taken apart in a moment, so as to occupy but little space when packed away, thus adding greatly to its convenience and lessening the danger of its being broken when not in use. 100 It can be jointed together in a moment, and the joint is firm and strong, and by reason of

the peculiar construction of the slotted upper end of the upper half the prop the prop will be firmly held or locked to the clothes-line, and thus prevented from being blown down by 5 the wind or, by any accidental push against it. It is very simple and strong in construction, and can be manufactured at a very small cost.

Having thus described my invention, what I claim, and desire to secure by Letters Patent 10 of the United States, is—

A clothes-line support the upper end of which is slotted near one edge, the broadest part of which slotted end is rounded upon its

upper inner edge and also provided with a recess running from its inner edge, the narrow 15 part of said end being adapted to be bent away from the broader or wider portion, and said slot extending below the bottom of said recess.

In testimony that I claim the foregoing as my own I have hereunto affixed my signature 20 in presence of two witnesses.

JOHN S. JAMESON.

Witnesses:
